No. 622,183.

Patented Mar. 28, 1899.

G. O. DRAPER.

WARP STOP MOTION APPARATUS.

(Application filed Oct. 14, 1898.)

UNITED STATES PATENT OFFICE.

GEORGE O. DRAPER, OF HOPE DALE, MASSACHUSETTS, ASSIGNOR TO THE DRAPER COMPANY, OF SAME PLACE AND PORTLAND, MAINE.

WARP-STOP-MOTION APPARATUS.

SPECIFICATION forming part of Letters Patent No. 622,183, dated March 28, 1899.

Application filed October 14, 1898. Serial No. 693,477. (No model.)

To all whom it may concern:

Be it known that I, GEORGE O. DRAPER, of Hopedale, county of Worcester, State of Massachusetts, have invented an Improvement in 5 Warp-Stop-Motion Apparatus, of which the following description, in connection with the accompanying drawings, is a specification, like letters on the drawings representing like parts.

10 My present invention relates to that type of warp-stop-motion mechanisms wherein the engagement and arrest of a normally-vibrating feeler is effected by the movement into abnormal position of one of a series of detectors maintained by normal warp-threads inoperative position, the arrest of the feeler operating to automatically effect the stoppage of the apparatus with which the stop-motion mechanism co-operates.

15 In my present invention the detectors have a vertical movement in a suitable guide having an opening for the admission of the feeler as it is vibrated under normal conditions, the feeler at such time moving into the guide below the lower ends of the detectors while they are under the control of intact and properly-tensioned warp-threads. If a warp-thread slackens or fails, its detector will drop into the path of and engage and arrest the feeler.

20 I have provided means for limiting the downward movement of a released detector and to support the lower end of the same against twisting or bending when engaged by the feeler.

25 My invention is herein illustrated as applied to a loom, a sufficient portion thereof being shown to be understood; but my invention is not restricted solely to use in a loom, as it may be applied equally well to other warp-treating mechanism, wherein it is desirable to effect stoppage of the apparatus automatically upon failure or slackness of one of the warp-threads.

30 Figure 1 is a longitudinal sectional view of a portion of a loom with one embodiment of my invention applied thereto, taken on the line $x-x$, Fig. 2, the major working mechanism of the loom being omitted, as it forms no part of this invention. Fig. 2 is a partial rear elevation of the apparatus shown in Fig. 1. Fig. 3 is an enlarged detail of a part of the ap-

paratus shown in Fig. 1, and Fig. 4 is an enlarged perspective detail of the limiting-stop for the detectors.

The harnesses H, whip bar or roll W, lease-rods L L', and the shipper-lever S may be and are of usual or well-known construction, and I have herein shown the detectors d as located back of the lease-rods, said detectors being shown as elongated thin metal plates, 55 provided each with a warp eye or opening d^x , and in Figs. 1 and 3 said detectors are shown as longitudinally slotted at their upper ends at d' to receive a guide-bar m, extended across the loom and supported in suitable brackets 60 M, attached to the loom-frame A. The bar m serves to steady the upper ends of the detectors when held in normal or full-line position by the warp-threads, as shown in Figs. 1 and 3.

70 The lower ends of the detectors enter loosely a box-like guide comprising front and back plates g g', the back plate being of greater depth than the front plate to leave a longitudinal opening at the front of the guide along 75 its lower portion for the entrance of the feeler a^x as the latter is normally vibrated, the path of movement of the feeler being below the detectors when controlled by their warp-threads. The said feeler a^x is herein shown as an angle-iron suitably secured to arms fast on a shaft a, having bearings m' (see Fig. 2) in the brackets M and vibrated by any suitable or desired mechanism, one form of which will be hereinafter described. The back plate g' 80 at its lower portion is opposite to the continuous edge of the feeler, and when a detector is released, as by the breakage or slackness of its warp-thread, it drops into dotted-line position, Figs. 1 and 3, so that one of its 85 upright edges will engage and arrest the feeler, the plate g' at such time acting as a back-stop to support a detector against the strain exerted thereon by the feeler.

90 In order to limit the downward movement 95 of a released detector and at the same time to prevent it from twisting laterally, I extend a bar h across the loom beneath said detectors, said bar having formed upon its upper edge, as shown best in Fig. 4, a series of deep 100 teeth h', the sides of which are oppositely inclined or beveled, the teeth in breadth being

equal to or greater than the width of a detector, said stop-bar being supported in suitable manner on the brackets M.

When a detector is released, as has been described, it drops, the inclined sides of the teeth directing its lower end into one of the notches, while those teeth at each side of the detector engage the latter and hold it from twisting or bending while subject to pressure or strain due to the engagement therewith by the feeler.

Inasmuch as the toothed stop-bar h prevents twisting of the detectors, I am enabled to dispense with a notched or toothed feeler.

15. To effect the normal vibration of the feeler, the rock-shaft a is herein shown as provided with an arm a³, extending oppositely to the feeler and having pivotally connected to it a bent arm a⁴, provided with a bunter a⁵ and a toe a⁶, coöperating with an edge cam D, preferably on the cam-shaft C, said bunter a⁵ being thus moved into and out of the path of one or more tappets f of a cam F, also fast on the shaft C. When the feeler is arrested, the bunter a⁵ is held up in the path of the tappet, engagement therewith swinging the arm a³ to the rear, said arm being slotted at a⁷ to receive a stud d⁸ on a short lever d¹⁰, pivoted at its upper end at d⁹ to a link d⁸, hooked around the cam-shaft at d¹¹, the other end of the link being jointed to the arm e of a rock-shaft e², provided with a knock-off arm e' for the skipper-lever. The lower end of the lever d¹⁰ and arm e are connected by a rod e², the joint e² acting as the lever-fulcrum when the bunter a⁵ is acted upon by the tappet-cam F, the swing of the upper end of said lever moving the link d⁸ longitudinally to operate the knock-off arm and release the shipper-handle S. The feeler is swung toward the detectors by the weight of the arm a³ and its connected parts, the reverse or outward swing of the feeler being effected by the cam D.

My invention is not restricted to the precise construction and arrangement herein shown, as the same may be modified or rearranged without departing from the spirit and scope of my invention.

Having fully described my invention, what I claim as new, and desire to secure by Letters Patent, is—

1. In an apparatus of the class described, a normally-vibrating feeler, stopping means operated by or through arrest of the feeler, a series of vertically-movable detectors normally controlled by the warp-threads and held out of the path of movement of the feeler, a guide for said detectors, and a stop-bar ex-

tended beneath the lower ends of the detectors and provided with upturned bevel-sided teeth to position the lower end of and prevent twisting of a detector when engaged by the feeler, the edges of the teeth being parallel with the width of the detectors.

2. In an apparatus of the class described, a normally-vibrating feeler, stopping means operated by or through arrest of the feeler, a box-like guide adjacent the feeler and having a longitudinal opening in its side to be normally entered by the feeler, a series of detectors vertically movable in said guide and when controlled by the warp-threads held with their lower ends above the side opening of the guide, the lower end of a released detector engaging and arresting the feeler, and a stop-bar beneath the open end of the guide, provided with upturned bevel-sided teeth to position the lower end and prevent twisting of a detector when engaged by the feeler.

3. In an apparatus of the class described, a normally-vibrating feeler, stopping means operated by or through arrest of the feeler, a series of vertically-movable thin, flat detectors controlled by normal warp-threads and thereby held in abnormal, inoperative position, a guide for the detectors, the lower end of a detector released by slackness or looseness of its warp-thread engaging and arresting the feeler, and means located below the feeler-path to act upon the flat opposite faces of a detector at or near its lower end when engaged by the feeler, to prevent twisting or bending of the detector.

4. In an apparatus of the class described, a normally-vibrating feeler, stopping means operated by or through arrest of the feeler, a series of vertically-movable thin, flat detectors controlled by normal warp-threads and thereby held in abnormal, inoperative position, a guide for the detectors, the lower end of a detector released by slackness or looseness of its warp-thread engaging and arresting the feeler, a back-rest for the rear edge of a detector when engaged by the feeler, a stop located below and to limit the downward movement of a released detector, and means below the feeler-path to act upon the opposite flat faces and prevent twisting of such detector.

In testimony whereof I have signed my name to this specification in the presence of two subscribing witnesses.

GEORGE O. DRAPER.
